UNITED STATES PATENT OFFICE.

GEORGE JOHN JABEZ MANVELL, OF LITTLEHAMPTON, ENGLAND.

GAGE-GLASS PROTECTOR FOR BOILERS.

SPECIFICATION forming part of Letters Patent No. 599,511, dated February 22, 1898.

Application filed May 3, 1897. Serial No. 634,936. (No model.)

To all whom it may concern:

Be it known that I, GEORGE JOHN JABEZ MANVELL, a subject of the Queen of Great Britain, residing at Littlehampton, in the county of Sussex, England, have invented a new or Improved Gage-Glass Protector for Boilers and such Like, of which the following is a specification.

This invention relates to a gage-glass protector for boilers and such like—that is to say, a removable cover to form a chamber to contain the gage-glass, so as to protect the latter from injury from external sources and also to prevent injury to the engineer or others and to prevent direct escape of steam or water into the stoke-hole or equivalent place in the event of the gage-glass bursting.

According to this invention the protector is suitably fitted or packed to form a closed chamber about the gage-glass, and an outlet is provided and fitted with an escape-pipe or connected to any existing escape or drain pipe to carry off any steam or water that may enter the chamber, so that the latter may not interfere with the movements of the engineer or other person in closing the cocks of the gage-glass.

The annexed drawings illustrate a gage-glass protector constructed to fulfil the above objects.

Figure 1 is a front elevation of a gage-glass with its ordinary fittings and showing the protector fitted thereon. Fig. 2 is a side elevation, and Fig. 3 is a horizontal section, illustrating the same parts.

A represents the gage-glass. B and C are the sockets holding the said gage-glass, and D E are the cocks thereof. Such sockets have usually cylindrical or similar parts b c, about which the protector may be fitted to form a close joint, usually with insertion of a packing-ring, as at b' c'.

F is the protector, which surrounds and encloses the gage-glass A. It is preferably made in two parts F' F², having flanges f f', to be connected together by bolts f² and thumb-nuts f³ or in any other convenient manner, so that it may be removable without difficulty for the replacement of a broken gage-glass.

f⁴ represents a packing-strip between the flanges f f'.

In place of two flanges the parts F' F² may

have a hinge or other connection along one side and be connected by bolts or the like on the other.

55

The front part of the protector is provided with an opening, in which glass of sufficient strength is inserted, as at G. This may be retained in place—for instance, between an exterior plate G' and an interior plate G². 60 The latter may be reinforced at G³.

In the construction illustrated the outlet of the protector is provided in the middle of the back part, as at H; but it may be at any other place. For instance, it may be a passage 65 through the metal of one of the sockets B C. It may be covered with a wire-gauze or with a grating to prevent it being closed by a portion of the broken gage-glass lying thereover.

I do not confine myself to the construction 70 here shown, but may vary the same within the spirit of this invention and in order that the operation of the invention may remain substantially the same.

Should the gage-glass break, the chamber F 75 will be filled with steam or water, or both, which will escape by the vent H and be carried off by the pipe leading therefrom. On observing the occurrence the engineer will close the cocks D E, so that no further water 80 or steam can enter the chamber F. The pressure in the latter having rapidly become equal to the exterior atmospheric pressure, the vent H being open, the protector may now be opened and wholly or partially removed in 85 order to replace the broken gage-glass with a new one. The protector may then be replaced and the cocks D E opened.

Having now particularly described and ascertained the nature of my said invention and 90 in what manner the same is to be performed, I declare that what I claim is—

A gage-glass protector consisting of two parts adapted to form a closed chamber surrounding said glass, said parts having packed 95 portions to engage the gage-glass sockets, one of said parts having a transparent portion, means for securing said parts together and a discharge-outlet for said chamber in one of said parts, substantially as described. 100

GEORGE JOHN JABEZ MANVELL.
